UNITED STATES PATENT OFFICE

GEORGE A. SIMONS AND GEORGE FREEBERG, OF MINNEAPOLIS, MINNESOTA, ASSIGNEES
TO SIMONS MILLWORK, INC., OF MINNEAPOLIS, MINNESOTA, A CORPORATION OF MINNESOTA

DESIGN FOR A BREAKFAST-NOOK BENCH

Application filed May 31, 1929. Serial No. 31,499. Term of patent 14 years.

To all whom it may concern:

Be it known that we, GEORGE A. SIMONS and GEORGE FREEBERG, citizens of the United States, residing at Minneapolis, county of Hennepin, and State of Minnesota, have invented a new, original, and ornamental Design for Breakfast-Nook Bench, of which the following is a specification, reference being had to the accompanying drawing, forming part thereof.

Figures 1 and 2 are opposite perspective views of the breakfast nook bench showing our new design.

We claim:

The ornamental design for a breakfast nook bench as shown.

GEORGE A. SIMONS.
GEORGE FREEBERG.
